GENERATOR OF ELECTRICAL OSCILLATORS
OF HIGH FREQUENCYMalcolm Ross Gavin, Wembley, England, assignor
to The General Electric Company Limited,
London, EnglandApplication January 2, 1942, Serial No. 425,429
In Great Britain November 5, 1940

7 Claims. (Cl. 250—36)

This invention relates to electrical oscillators, adapted to generate oscillations of high frequency, of the type comprising a pair of thermionic grid-controlled valves operated in push-pull and feeding a resonant circuit of which at least part consists of a concentric line.

Two known oscillators of this type are shown diagrammatically in Figures 1 and 2 respectively of the accompanying drawing. Figures 3 and 4 show diagrammatically two embodiments of the invention.

In Figure 1, a pair of triodes, each consisting of a cathode 1 or 1', a concentric grid 2 or 2', and a concentric anode 3 or 3', are connected to the opposite ends of a straight concentric line, consisting of inner conducting tube or rod 4 and outer conducting tube 5. The electrical length of the line is $\lambda/2$, where λ is the wave-length of the oscillations. Each cathode lead 6 or 6' is the inner member of another concentric line whose outer member is 1 or 1'; 1 and 1' are connected by the screen 8 surrounding the line 4, 5; the cathode leads are tuned by means of the bridges 9, 9'. The anode supply lead 11 can be attached to any point on the tube 5, since this conductor is grounded for high frequency oscillations; the grid is fed by a lead 10 attached to the electrical centre of the tube or rod 4 and passing through a hole in conductor 5.

In this oscillator the two cathode leads have to be tuned separately. In order to avoid this inconvenience the modification shown in Figure 2 has been used. Here the concentric line 4, 5 has been bent round so that the cathode leads emerge side by side; they then form a parallel line which can be tuned by the bridge 12.

But now a lower limit is set to the length of the concentric line 4, 5 and therefore, since this length is about $\lambda/2$, an upper limit is set to the possible frequency of the oscillations generated. (It is to be observed that since the system is an oscillator, it is difficult to prevent it from oscillating in its fundamental mode; the possibility of the length's being a multiple of $\lambda/2$ is excluded.) Furthermore the electrodes of the valves will be enclosed in envelopes 14, 14'. The line must be long enough to emerge from the envelope and to extend over the distance between the electrode systems when the envelopes are in contact. The object of this invention is to abolish the limit set by this consideration and thus to raise the upper limit of the frequency of oscillation.

Figs. 3 and 4, which show diagrammatically two embodiments of the invention respectively, indicate how this object may be attained. Speak-

ing broadly, the connection between the two valves in Figure 2 is cut off; the electrical length of each remaining stump of the concentric line 4, 5 has now to be $\lambda/2$. The free ends of the stumps (4, 5), (4', 5') may emerge from the envelopes 14, 14' as in Figure 3 or may be contained within the envelopes as in Figure 4. The grid lead 10 is branched; the end of each branch is attached to a tube or rod 4, 4', preferably at a point at an electrical distance $\lambda/4$ from its free end as shown in Fig. 4. If these points lie within the envelopes, but another part of the line lies outside the envelope, it may be desirable to attach the grid lead at a point outside the envelope which is not a node; this can be done if, as indicated in Fig. 3 chokes 13, 13' are inserted between the common part of the lead 10 and the ends of the branches attached to the tubes or rods 4, 4'.

The leads for heating the cathode can be arranged as is usual in the arrangement shown in Figure 2. The leads 6, 6' each consist of a pair of concentric conductors insulated from each other; one end of the heating element 17, 17' is connected to the outer member and the other to the inner member. The parts shown in Figure 3 or 4 may be surrounded by a screen (not shown) performing the same function as the screen 8 in Figure 1.

According to the invention, an electrical oscillator of the type specified, wherein the said valves are arranged side by side and so that their cathode leads form a parallel line terminable by means of a bridge, comprises a pair of concentric lines, one connected to the grid and anode of one said valve and the other connected to the grid and anode of the other said valve, the said lines each being open at the end remote from the cathode of the valve with which it is associated and the electrical length of each said line being substantially $\lambda/2$, where λ is the wave length of the oscillations that the oscillator is adapted to generate.

What I claim as new is:

1. A high-frequency electrical oscillator comprising a pair of thermionic grid-controlled valves operating in push-pull, wherein the said valves are arranged side by side and their cathode leads form a parallel line terminable by means of a bridge, the oscillator also comprising a pair of concentric lines, one connected to the grid and anode of one said valve and the other to the grid and anode of the other said valve, the said lines each being open at the end remote from the cathode of the valve with which it is associated and the electrical length of each said line being

$\lambda/2$, where λ is the wave-length of the oscillations that the oscillator is adapted to generate.

2. A high-frequency electrical oscillator according to claim 1 wherein each said open end of a line lies within the envelope of the valve with which it is associated.

3. An electrical conductor according to claim 1 wherein at least one of the said open ends lies outside the envelope of the valve with which it is associated, wherein a grid lead is attached to a point on one of the said lines that is outside the envelope and is not a node for the oscillations, and wherein the said lead contains a choke.

4. An electrical oscillator according to claim 1 wherein each said cathode lead is a concentric line consisting of a pair of concentric conductors, and wherein one end of the cathode heater is connected to one member of the pair and the other to the other member of the pair.

5. A high-frequency electrical oscillator according to claim 1 wherein each said open end of a line lies within the envelope of the valve with which it is associated, wherein each said

cathode lead is a concentric line consisting of a pair of concentric conductors, and wherein one end of the cathode heater is connected to one member of the pair and the other to the other member of the pair.

6. An electrical conductor according to claim 1 wherein at least one of the said open ends lies outside the envelope of the valve with which it is associated, wherein a grid lead is attached to a point on one of the said lines that is outside the envelope and is not a node for the oscillations, and wherein the said lead contains a choke wherein each said cathode lead is a concentric line consisting of a pair of concentric conductors, and wherein one end of the cathode heater is connected to one member of the pair and the other to the other member of the pair.

7. A high-frequency oscillator according to claim 1 wherein each said thermionic valve is a triode whose anode and grid are cylinders surrounding and concentric with the cathode and are effectively continuations of the conductors of the said concentric line connected to them.

MALCOLM ROSS GAVIN.
